UNITED STATES PATENT OFFICE.

LAURA L. HARFORD, OF BERKELEY, CALIFORNIA.

BOOK-HOLDER.

1,194,016.

Specification of Letters Patent.

Patented Aug. 8, 1916.

Application filed March 9, 1915. Serial No. 13,110.

To all whom it may concern:

Be it known that I, LAURA L. HARFORD, a citizen of the United States, and a resident of Berkeley, county of Alameda, and 5 State of California, have invented a certain new and useful Book-Holder, of which the following is a specification.

The invention relates to a device for holding books, such as copy books and stenographers' note books in an open position, so 10 that the matter or notes thereon may be readily read and copied.

An object of the invention is to provide a book holder to which the open book is securely and quickly attachable.

Another object of the invention is to provide a book holder which may be folded and which is simple and cheap in construction.

The invention possesses other advantageous features, which, with the foregoing, 20 will be set forth at length in the following description, where I shall outline in full that form of the invention which I have selected for illustration in the drawings accompanying and forming part of the present specification. The novelty of the invention will be included in the claim succeeding said description. From this it will be apparent that I do not limit myself to the showing 25 made by said drawings and description as I may adopt many variations within the scope of my invention, as set forth in said claim.

Referring to said drawings: Figure 1 is 30 a perspective view of the holder of my invention with an open book arranged thereon and attached thereto. Fig. 2 is a perspective view of the holder of my invention. Fig. 3 is a modified form of the holder. 35 Fig. 4 is a plan of a fragment of the holder.

The holder of my invention is adapted to be used in supporting books, such as copy books and note books, in an open position with the pages disposed at an angle to the 40 horizontal so that the matter thereon may be readily observed and read, and it is particularly designed to be used by typewriter operators. The holder comprises a frame of

any suitable construction which is adapted to lie on a desk, the frame shown in Figs. 50 1 and 2 being composed of the longitudinal members or bars 2-3 and the cross or transverse members or bars 4-5, which are secured to the longitudinal members. Means are provided on the frame for clamping the 55 covers of a book to the frame, so that when in use, the book and frame form a substantially rigid structure. The ends of the longitudinal members 2-3 are bent upward and backward at their ends producing the 60 inclined lips 6 against which the covers of the book are clamped by the spring clamps 7. The clamps 7 are attached to the members 2-3 and are arranged adjacent the lips 6 and the upper ends of the clamps are preferably curved away from the lips 6 to form 65 V-shaped clamps to permit the ready insertion of the book covers. The leaves of the book are, therefore, free and may be readily turned. Normally, the clamps 7 contact 70 with the lips 6, but when the book covers are inserted, the covers lie between the clamps and the lips. The frame is also provided on its under side with pads 8 of soft material such as felt, so that the frame will 75 not mar the desk on which it is placed.

In the construction shown in Fig. 3 the frame is composed of the longitudinal members 12-13 which are pivoted together, preferably at the center, so that the holder 80 may be folded to occupy smaller space when not in use. In this construction the lips 6 on the ends of the longitudinal members are inclined in the horizontal plane to the longitudinal members, so that when the members 85 are separated and lie at an angle to each other, the lips at the front and rear are parallel and each pair of lips is aligned, that is, the lips 6 are so arranged on the members 12-13 that the plane of the lip intersects the plane of the member in a line which makes an angle other than a right angle to the longitudinal axis of the member.

I claim:

A book holder comprising a frame, a 95 plurality of upwardly and backwardly in-

clined rigid fixed lips formed integrally with the frame and spaced apart transversely at the front and rear ends thereof, and L-shaped spring members attached to the outside of said frame, adjacent said lips to form V-shaped clamps therewith opening upwardly adapted to receive the covers of a book.

In testimony whereof, I have hereunto set my hand at San Francisco, California, this 15 3rd, day of March, 1915.

LAURA L. HARFORD.

In presence of—
H. G. PROST,
N. THREW.
